SUPERCHARGER FOR INTERNAL COMBUSTION ENGINES

Filed May 1, 1930

Gotthard S. Osterberg

INVENTOR.

UNITED STATES PATENT OFFICE

GOTTHARD S. OSTERBERG, OF TIDAHOLM, SWEDEN, ASSIGNOR TO ROBERT SUCZEK, OF GROSSE POINTE PARK, MICHIGAN

SUPERCHARGER FOR INTERNAL COMBUSTION ENGINES

Application filed May 1, 1930. Serial No. 449,070.

The invention relates to superchargers driven by the exhaust gases from an internal combustion engine through the medium of a turbine.

5 The main object of my invention is to create an efficient and cheap unit producing compressed air for supercharging internal combustion engines or any other purpose.

Another object of this invention is to prevent the turbine vanes from overheating 10 through the exhaust gases, by cooling them with the air flowing through the compressor.

With these and other advantages and objects of my invention in view, together with 15 means whereby the same may be carried out, my invention consists in the arrangement, construction and combination of various parts of my new device and method of its operation as described in the specification, 20 claimed in the claims and illustrated in the accompanying drawing.

It will be understood that some of the particular constructions and arrangements embodied and shown, have been shown for illustrative purposes only and that the invention as defined by the claims thereunto appended may be otherwise embodied without departure from the spirit and scope of the invention.

30 Fig. 1 is a longitudinal section through the turbine and the blower according to my invention.

Fig. 2 is a part of a transversal section along line 2—2 through Fig. 1.

35 Fig. 3 is a development of the turbine wheel buckets partly in section.

As shown in Fig. 1 hub 4 mounted on shaft 5 and supported by bearings 6 and 7 carries the blower vanes 8 and also the turbine vanes 9. The turbine consists of a 40 hollow drum 10 and the vanes are either cast or milled into the periphery of such drum in the form of buckets 9. The vanes 8 of the blower connect the drum 10 to the hub 4.

11 is the motive fluid inlet, in this case the exhaust gases from an internal combustion engine. 12 is the nozzle passage discharging the expanded gases into the buckets of the turbine. The spent gases, after performing the work in the turbine, leave the housing at 13.

The air enters the blower impeller at 14, flows radially out through the action of the centrifugal force, and when approaching 55 the wall forming the turbine buckets it is forced to perform a sharp turn into passage 15 formed by baffles 16 and 17, both carried by the discharge nozzle 18, supported by the bracket 19 and the turbine housing 20. Flange 21 may be connected to the engine intake manifold or to any other desirable place where the compressed air is required.

To nozzle 18 is connected by ribs 22 a 60 guiding core 23 which carries baffle plate 16 and bearing 7 with gland 24. The other bearing 6 is carried by a tubular member 25 ribbed in a convenient way to housing 70 20 by ribs 26.

The expanding exhaust gases or the motive fluid, after leaving the nozzle at high velocity, flow into the semi-circular buckets 9, are diverted therein by 180 degrees, relative to the bucket, giving up some of their 75 velocity which is converted into work by the turbine drum 10 and transmitted through the blower vanes 8 into air pressure rise.

While flowing through the buckets the 80 hot gases heat up the walls of the turbine drum and of the buckets to such an extent that it is necessary to cool them. This I accomplish very effectively by the arrangement of the turbine buckets on the periphery 85 and forcing the air issuing from the blower vanes to impinge against the drum periphery with high velocity and performing a sharp turn of almost 180 degrees by changing its direction from radially outward to radially inward.

The turbine does not require any explanation and anybody versed in the art will see that it acts the same way as a low pressure Pelton wheel. The motive fluid enters into the chamber 27, expands in the nozzle passage 12 formed by the nozzle vanes 28 and from there flows into the buckets as mentioned before.

What I claim is:

- 10 1. A supercharger for internal combustion engines comprising a rotating drum, a passage within the drum for compressing and conducting the air, a turn in such passage, turbine vanes outside the drum mounted at the turn in such passage, the turbine vanes receiving exhaust gases from the engine and diverting the gases more than 90 degrees.
- 15 2. A compressor for internal combustion engines comprising a stationary element having the purpose of a housing, a hollow rotor within the stationary housing, means to conduct fluid to be compressed into the inside of the rotor, means to raise the pressure of the fluid within the rotor, means to guide the fluid within the rotor first in a direction away from the axis of the rotor and thereafter towards the axis, turbine buckets disposed on the periphery of the
